[57] **ABSTRACT**

A heat exchanger for removing moisture from compressed air and other gases in which the precooling, cooling and reheating sections are in telescoped relation.

16 Claims, 3 Drawing Figures

FIG. 1

FIG. 2

FIG. 3

HEAT EXCHANGER FOR COMPRESSED AIR DRYER

This invention is intended to increase the efficiency and reduce the cost of manufacture and operation of heat exchangers for removing moisture from air or other gases. In a preferred form, the heat exchanger is shown for removing moisture from compressed air but other uses are obviously possible.

In the drawing, FIG. 1 is a section through a heat exchanger for removing moisture from compressed air and the like, FIG. 2 is a section on line 2—2 of FIG. 1, and FIG. 3 is a section through another embodiment.

In FIG. 1 there is shown a tank having side walls 1 and upper and lower headers 2, 3. At the lower end of the side walls are inlet and outlet fittings 4, 5 for connection in a compressed air line. The tank and its fittings are constructed to withstand the air pressure. The tank is shown as of circular cross section but obviously other shapes could be used. Within the tank are heat exchange passageways 6, 7, 8, 9 in telescoping relation to each other. The heat exchange passageway 6, which is outermost, is formed by a wall 10 spaced inward from the inner surface of the wall 1 and extending between an annular lower header 11 and an annular upper header 12. The lower header 11 is fixed to the side wall 1 of the tank below the inlet fitting 4 and supports the wall 10 and also closes the lower end of the passageway 6 so that the incoming air is directed upward in the direction of arrow 13. The header 12 at the upper end of the wall 10 directs the flow from the outlet of passageway 6 in the direction of arrow 14 to the inlet end of passageway 9 formed between a wall 15 depending from the header 12 and a conduit 16 for a refrigerant. The refrigerant enters the lower end of conduit 16 as indicated by arrow 17 and flows out the upper end as indicated by arrow 18. The outer surface of the conduit 16 may be provided with spikes or fins 19 or other expedients for increasing the heat exchange surface. Expedients for increasing the heat exchange surface may obviously be used for the other walls forming heat exchange passageways. While flowing through the passageway 9, the air temperature is lowered below its dew point and moisture and other condensables are condensed, falling into a sump 20 formed by the header 3. Dirt entrained in the air also falls into the sump. A drain fitting 21 is provided to remove excessive liquid accumulation in the sump. Some liquid in the sump is advantageous since this liquid is cooled by the refrigerant in conduit 16 and therefore provides a further heat exchange surface for lowering the dew point of the air and thereby removing moisture. The enlarged space 22 between the outlet 23 of passageway 9 and the inlet 24 of passageway 8 encourages moisture drop out and discourages entrainment of moisture in the air entering the inlet of passageway 8.

The air entering the lower end of passageway 8 flows upward as indicated by arrow 25 and at its upper or outlet end 26 is deflected downward by header 12 into the inlet end 27 of passageway 7 as indicated by arrow 28. Passageway 7 is in heat exchange relation to wall 10 of passageway 6 and also to wall 29 of passageway 8. The heat exchange relation to wall 10 serves to precool the incoming air flowing in the direction of arrow 13. The heat exchange relation to the wall 29 is minimized by making wall 29 of a poor heat conductor. While the

inlet air flowing in the direction of arrow 13 is being precooled, the air flowing downward through passageway 7 in the direction of arrow 30 is being reheated. At the lower or outlet end of passageway 7 the header 11 deflects the air to the outlet fitting 5.

The walls 10, 15, 29 which form the heat exchanging passageways are all supported by the header 11. These walls may be of thin metal since none of these walls is required to stand the operating pressure of the air. Both headers 11 and 12 also have the function of directing the air flow through the heat exchanger passageways, as described above. The structure has high thermal efficiency because the warm incoming air is at the outside of the tank and the cold or dehydrated air is at the center of the tank. Sharing of walls of the heat exchanger passageways improves the thermal efficiency by direct conduction of heat from the air through the metal walls. Wall 15 is shared by passageways 8, 9. Wall 29 is shared by passageways 7, 8. Wall 10 is shared by passageways 6, 7. The structure also makes efficient use of space due to the sinuous air flow of the heat exchanging surfaces. The structure further simplifies the construction and reduces the space requirements.

In FIG. 3 there is shown a modification in which the 25 dew point of the air is lowered by chilled liquid spray and in which the inlet and outlet for the compressed air is at the top of the tank rather than at the bottom. Obviously the cooling apparatus of FIG. 3 could be substituted in FIG. 1 and vice versa.

In the structure of FIG. 3, the tank 40 has upper and lower headers 41, 42 and inlet and outlet fittings 43, 44 for compressed air. These parts are sized to withstand the air pressure. Within the tank are heat exchange passageways 45, 46, 47, 48 in telescoping relation to each other. The passageway 45 is formed by a wall 49 and the inner surface of side wall 40 of the tank. The wall 49 is fixed at its upper end and supported by the header 41 and at its lower end is fixed to an annular header 50 extending between wall 49 and a wall 51 which defines the passageway 48. The compressed air entering inlet 43 is compelled to flow downward through the passageway 45 and enters the lower end of passageway 48 and flows upward as indicated by arrow 52. While flowing up through passageway 48, the air is cooled by a refrigerated liquid spray obtained from a liquid chiller 53 and circulated by a pump 54 from a sump 55 in header 42 to a spray head 56 discharging into the upper end of passageway 48. A series of staggered baffles 57 provide an extended gas and liquid contact interface between the compressed air and the chilled liquid. This results in cooling of the compressed air below its dew point so that the moisture is absorbed by the liquid which falls into the sump as indicated by drops 58. The liquid in the sump provides a further heat exchange surface for cooling the air entering the lower end of passageway 48. Excess accumulation of liquid in the sump is prevented by a valve 59. If the liquid is chilled below the freezing point of the moisture, an anti-freeze is required. This is obtained from an injector 60 having a sensing element 61 responding to the freezing temperature of the liquid in the sump which injects anti-freeze through line 62 as required by the sensor. When the injector is used, the outlet from the control valve 59 would ordinarily lead to anti-freeze recovery apparatus such as a still.

The cooled air leaving the upper or outlet end of the passageway 48 flows downward through passageway 47

formed by wall 51 and a surrounding wall 63 which is supported by the header 41. Air leaving the lower or outlet end of passageway 47 flows upward into the inlet end of passageway 46 formed between the walls 49 and 63. At the outlet end of the passageway 46 the air is deflected by the header 41 into the outlet fitting 44.

In the operation, the incoming compressed air from inlet fitting 43 is precooled by the air in passageway 46. This heat exchange both precools the incoming air and reheats the outgoing air leaving fitting 44. The air is further cooled by contact with the liquid in the sump 55 and by the liquid spray in passage 48.

In both forms of the invention, the heat exchange passageways are in telescoping relation, improving the thermal efficiency and decreasing the space requirements and the cost of production. Only the tanks and its headers are sized to withstand the operating pressure. The internal walls are designed for heat transfer and not for pressure.

What is claimed is:

1. Apparatus for dehumidifying air or other gas comprising a plurality of telescoped passageways each having an inlet at one end and an outlet at the opposite end, a first passageway being outermost with its inlet receiving air to be dehumidified, a second passageway being innermost with its inlet receiving the air from the outlet of the first passageway and conducting such air in the opposite direction to the direction of flow in the first passageway and having therein refrigerating means in heat exchange relation to such air, a third passageway surrounding and in heat exchange relation to the second passageway with its inlet receiving the air from the outlet of the second passageway and conducting such air in the same direction as the direction of flow in the first passageway, and a fourth passageway between and in heat exchange relation to the first passageway with its inlet receiving the air from the outlet of the third passageway and conducting such air in the opposite direction to the direction of flow in the first passageway, the flow being sequentially through the first, second, third and fourth passageways.

2. The apparatus of claim 1 in which the third passageway shares a wall with the second passageway and

also shares a wall with the fourth passageway.

3. The apparatus of claim 1 in which the fourth passageway shares a wall with the first passageway.

4. The apparatus of claim 1 having a tank with inlet and outlet fittings, the first passageway being connected to the inlet fitting and formed between the inner surface of a side wall of the tank and a first wall spaced inward from said surface and the fourth passageway being connected to the outlet fitting and formed between said first wall and a second wall spaced inward from said first wall.

5. The apparatus of claim 4 in which a third wall forms the second passageway and is spaced inward from the second wall to form the third passageway.

10 6. The apparatus of claim 5 in which the tank has upper and lower headers and the lower header provides a sump below said second and third walls.

15 7. The apparatus of claim 6 in which the sump is refrigerated to provide a further cooling surface.

20 8. The apparatus of claim 1 in which the refrigerating means comprises a chilled liquid spray.

9. The apparatus of claim 1 in which the refrigerating means comprises a conduit carrying in said second passageway a refrigerating medium.

25 10. The apparatus of claim 8 in which the chilled liquid is a solution with a freezing point below the normal freezing point of water.

11. The apparatus of claim 4 in which the first and second walls are supported by a header fixed to the tank.

30 12. The apparatus of claim 5 in which the third wall is supported by said header.

13. The apparatus of claim 5 in which the tank has upper and lower headers and the lower header provides a sump below said third wall.

35 14. The apparatus of claim 5 in which the tank has upper and lower headers and the lower header provides a sump below said first, second and third walls.

15. The apparatus of claim 13 in which the sump is refrigerated to provide a further cooling surface.

40 16. The apparatus of claim 14 in which the sump is refrigerated to provide a further cooling surface.
